His Attorney.

UNITED STATES PATENT OFFICE.

HENRY E. WARREN, OF ASHLAND, MASSACHUSETTS, ASSIGNOR TO WARREN CLOCK COMPANY, OF ASHLAND, MASSACHUSETTS, A CORPORATION OF MAINE.

TIME-INDICATING APPARATUS.

1,409,502.

Specification of Letters Patent. Patented Mar. 14, 1922.

Original application filed April 15, 1918, Serial No. 228,633. Divided and this application filed June 18, 1920. Serial No. 390,014.

To all whom it may concern:

Be it known that I, HENRY E. WARREN, a citizen of the United States, residing at Ashland, county of Middlesex, State of 5 Massachusetts, have invented certain new and useful Improvements in Time-Indicating Apparatus, of which the following is a specification.

My invention relates to time indicating 10 apparatus, and more particularly to means whereby such apparatus may be regulated and set.

This application is a division of an application filed in my name, Serial No. 15 228,633, filed April 15, 1918, entitled "Time indicating apparatus" and assigned to the Warren Clock Company.

One of the objects of my invention is to provide means for accurately setting a time 20 piece so that it may agree with standard indications such as the time signals from Washington and to bring this about in an easy and gradual way without the necessity of a hand setting or by other mechanical methods. Another object is to regulate 25 or set the time piece without any physical contact with any of its moving parts. Other advantages and objects of my invention will appear as the description proceeds.

30 My invention contemplates the use of an oscillating member for timing the clock movement having at least a portion thereof of magnetic material, preferably a permanently magnetized steel bar. In an ordinary 35 clock movement the oscillating member of course takes the form of a pendulum of which the bob may carry the permanent magnet heretofore referred to. With such a construction it is possible to vary the period 40 of the oscillating member by electromagnetic means, such for example as a coiled wire placed so that it may become active either to attract or repel the magnetic member carried by the pendulum. By varying 45 the strength of current flowing through the coil, the force of attraction or repulsion may be varied and any desired period of vibration of the oscillating member may be obtained within prescribed limits. With such 50 an apparatus as described above, actual physical contact with any of the clock parts

is entirely obviated and the period of the pendulum may be varied by means of an external current varying device. This result attains great importance when it is 55 necessary to set the clock; that is, to bring its indication into coincidence with the indications from a standard source such as the signalled observatory time at Washington. When it is necessary to set the clock, 60 I provide means for varying the period of vibration of the oscillating member for a limited plurality of oscillations only, and I attain this result by so arranging the clock movement that it breaks the electric 65 circuit which energizes the period varying coil after the clock train has moved a distance corresponding to a predetermined elapsed time. Preferably I so arrange the circuit for the coiled conductor that said 70 circuit may be closed manually, but is automatically opened by the clock movement itself, as stated above.

It is possible with my invention, therefore, to attain extreme precision for setting 75 and regulating the clock, because the value of the current sent through the coiled conductor may be set within very close limits to produce its desired effects.

The construction and mode of operation 80 of my invention may be understood by reference to the accompanying drawing, in which the single figure shows diagrammatically the circuit arrangement and the operating parts of the clock to be regulated.

85 Referring now more in detail to the drawing, I show a standard time piece 1, the rate of which is dependent upon the rate of oscillation of the pendulum 2, carrying at its lower end a bob 3. This clock is of the same 90 type as shown and described in my prior application hereinbefore referred to, and since it is entirely immaterial so far as my present invention is concerned just what form of clock movement is to be regulated, 95 I shall not describe it in any greater detail. Suffice it to say that an escapement is utilized which is in operative relation to the clock hands, one of which is shown at 4. An intermediary gear 5 is used to drive the 100 hands, which indicate the time of day on a clock dial 6. The means for varying the

period of oscillation of the pendulum 2 is shown as an electro-magnetic device, comprising two coiled conductors 7 and 8 placed immediately below the pendulum bob 3 which carries at its lower end a bar of magnetic material 9. This bar 9 is preferably permanently magnetized and made of a material such as hard steel so that it may retain its magnetism indefinitely. For regulating the clock, so that its rate may be accurate, the coil 7 is used. This coil is connected into a potentiometer circuit so that the current flowing therethrough may be gradually varied or reversed. This potentiometer circuit comprises the two sources of electricity shown in this case as cells 10 and 11, placed in series with a resistance 12. The energizing circuit for the coil 7 is tapped off from this circuit, one terminal of the coil 7 being connected by wire 13 to an intermediate point of resistance 12 variable by means of the switch arm 14, while the other terminal of said coil is connected by wire 15 between the two cells 10 and 11 which preferably have equal E. M. F.'s. It is evident that when the blade 14 contacts with the exact midpoint of the resistance 12 no current flows through coil 7 because its terminals are connected to points of equal potential. By moving the switch arm 14 in one or the other direction a current may be sent through the coil 7 in either direction so as to attract or repel the permanent magnet 9. For convenience in performing the regulating operation, I provide a box shown diagrammatically at 16 which houses the regulating resistance and switch arm 14. I may also use a scale 17 showing accurately how much the switch arm 14 must be moved so as to correct by the required amount the period of the pendulum. This circuit arrangement is so made that the variation of the period of the pendulum may be made permanent.

I provide means similar to that already described, for temporarily altering or varying the period of the pendulum so that the clock may be brought to exact coincidence with a standard indication within a reasonably short time. In the drawings I show by way of example a box 18 having the same external appearance as the regulating box 16. The resistance 19 in this box is in series with the cells 10 and 11. The operations of the setting means and the regulating means are entirely separated and distinct and have nothing in common except that the same sources of current 10 and 11 are used. The coiled conductor 8 placed near the pendulum bob is used for exerting an electro-magnetic force upon the magnet 9, just as the coiled conductor 7. The terminals of the coil 8 are connected respectively to switch arm 20 which connects to intermediate points on the resistance 19 and by wire 15 to a point located between the cells 10 and 11. The wire 21 which connects one of the terminals of the coil 8 to the switch arm 20 is broken at a point 22, at which point there is located a manually operated switching means 23, which may be conveniently operated by depressing a knob 24. This switching means is so arranged that a catch holds this means closed after the knob 24 is depressed. The switching means 23, as shown, comprises a spring blade supported on a post 25 electrically connected with a wire 26 leading to the switch arm 20 of the box 18 used for setting the clock. A contact tip 27 is carried at the other end of this spring blade 23, which contact tip is adapted to engage the stationary contact 28 connected by the wire 21 to a terminal of the coil 8. The catch for keeping contact 27 in engagement with contact 28 is shown in this case as a member 29 pivoted on a stationary part of the clock frame, as shown at 30, and carrying a hooked portion 31 adapted to engage a shoulder 32 on a rod 33 in rigid connection with the knob 24. Other means of course may be utilized for holding the two contact points together. It is evident that for closing the switch it is merely necessary to push down on the knob 24; this movement causes the shoulder 32 to be moved below the hooked member 31. Said hooked member 31 thus engages the shoulder and keeps the rod 33 in its depressed position, due to the weight of the arm 34 of the catch 29. In order to guide the rod 33 in its up and down movement I provide a stationary guide 35 in which the enlarged portion 36 of said rod may enter, as clearly shown in the drawing. The circuit for coil 8, however, may be opened at the contact tips 27 and 28 by the clock movement itself, so that the setting means is only active for a relatively short period. For performing this function, I provide a pin 37 carried by one of the gears operating the hands of the clock, in this case shown as the hour hand gear 5, which rotates once in twelve hours. The pin 37 serves to lift the arm 34 of the pivoted catch 29 so that the hooked member 31 is disengaged from the shoulder 32 and the rod 33 moves upward, due to the springiness of the contact arm 23, into the position shown in the drawing. For convenience in performing this catch releasing operation, I provide a bent over portion 38 on the arm 34 of the catch. On the setting box I provide a scale 39, showing where the switch arm 20 must be set for producing a desired effect on the period of the pendulum.

The mode of operation of my invention is clear from the foregoing description. As an example, suppose that the clock registers ten seconds fast at the time of the noon signal from Washington; the regulating switch arm 14 is set so as to correct once for all the period of the pendulum. The

switch arm 20, however, is set in such a position that in a succeeding twelve hours ten seconds will be lost by the clock movement. At the same time the knob 24 is depressed 5 so that the catch 29 may become active to hold the circuit including the setting coil 8 in operative relation. At the end of a complete revolution of the gear wheel 5 the pin 37 serves to release the catch 29 and 10 the circuit is thus opened at the contacts 27 and 28. If the indicating means comprising the scale 39 and pointer 40 carried by the switch arm 20 is accurately calibrated, the period of the pendulum 3 has been varied 15 during the revolution of gear wheel 5 to such an extent that the ten seconds is lost. The regulating means is, however, active at all times to cause the clock to have a fixed rate and this means is entirely independent 20 of the setting means described above.

While I have shown in the accompanying drawings one embodiment of my invention, I do not desire to be limited thereto but aim to cover in the appended claims all modifications falling fairly within the scope of my invention.

What I claim as new and desire to secure by Letters Patent of the United States, is,—

1. In an instrument of the character described, a clock movement, a pendulum for timing said movement, means for varying the period of said pendulum, and means driven by said clock movement for rendering said period varying means inoperative 35 after a predetermined elapsed time.

2. In an instrument of the character described, a clock movement, a pendulum for timing said movement, electromagnetic means for varying the period of said pendulum, a manually set contact device in the circuit energizing said electromagnetic means, and means driven by said clock movement for opening said contact device at a predetermined time.

45 3. The combination with a timing device provided with an oscillating magnetic member, of a coiled conductor located in the field of said magnetic member, and means for passing a measured current for a limited time through said coiled conductor for setting the timing device.

4. The combination with a timing device provided with an oscillating magnetic member, of a coiled conductor located in the field 55 of said magnetic member, means for passing a measured current for a limited time through said coiled conductor for setting the timing device, and an indicator cooperating with said means for showing the effect of the 60 current upon the setting of the timing device.

5. The combination with a timing device provided with an oscillating member, of means for varying the period of said member, and means driven by said timing de-

vice for rendering said period varying means inoperative after a predetermined elapsed time.

6. In an instrument of the character described, a clock movement, an oscillating member for timing said movement, means for varying the period of said member, means for manually setting said period varying means into operation, and means driven by said clock movement for rendering said period varying means inoperative.

7. In an instrument of the character described, a clock movement, a pendulum for timing said movement, means for varying the period of said pendulum, a manually set catch for rendering said period varying means operative, and an operating member for releasing said catch driven by the clock movement.

8. In an instrument of the character described, a clock movement, a pendulum for timing said movement, electromagnetic means for varying the period of said pendulum, a switch in the circuit energizing said electromagnetic means, a pivoted catch for holding said switch in operative position, and means driven by said clock movement for releasing said catch at a predetermined time.

9. The combination with a timing device provided with an oscillating magnetic member, of a coiled conductor located in the field of said magnetic member, means for energizing said coiled conductor, and means driven by said timing device for rendering said energizing means ineffective.

10. In a timing device, means for setting said device comprising means for temporarily exerting a force upon a movable part of said timing device without physical contact therewith, and means for varying said force.

11. In a timing device, an oscillating member, means for setting said device comprising means for temporarily exerting a force upon said oscillating member without physical contact therewith, and means for varying said force.

12. In an instrument of the character described, a clock movement, a pendulum for timing said movement, means for setting the instrument comprising means for temporarily exerting a force upon said pendulum without physical contact therewith, and means for varying said force.

13. In a timing device, time indicating means, an oscillating member to control said means, and means for setting said timing device comprising means for exerting a force upon a movable part of said timing device without physical contact therewith and during a limited plurality of oscillations of said oscillating member.

14. In a timing device, time indicating means, an oscillating member to control said

means, means for controlling the period of oscillation of said oscillating member, and means for varying the period of a limited plurality of oscillations of said member. for varying the period of a limited plurality of oscillations of said member, and means to indicate the degree of effectiveness of said period varying means. 10

5 15. In a timing device, time indicating means, an oscillating member to control said means, means for controlling the period of oscillation of said oscillating member, means In witness whereof, I have hereunto set my hand this second day of June, 1920.

HENRY E. WARREN.
